Primary Examiner — Phillip S Hyder(74) *Attorney, Agent, or Firm* — Sheridan Ross P.C.(57) **CLAIM**

The ornamental design for a folding knife, as shown and described.

DESCRIPTION

FIG. 1 is a perspective view of the folding knife;
 FIG. 2 is a front elevation view thereof;
 FIG. 3 is a rear elevation view thereof;
 FIG. 4 is a right elevation view thereof;
 FIG. 5 is a left elevation view thereof;
 FIG. 6 is a top plan view thereof;
 FIG. 7 is bottom plan view thereof; and,
 FIG. 8 is a perspective view of the folding knife in a closed position.

The broken lines depict portions of the folding knife in which the design is embodied that are not considered part of the claimed design.

1 Claim, 4 Drawing Sheets(56)
